FUEL SAVING DEVICE FOR INTERNAL COMBUSTION ENGINES

Filed Nov. 20, 1936

UNITED STATES PATENT OFFICE

2,080,302

FUEL SAVING DEVICE FOR INTERNAL
COMBUSTION ENGINES

Leonard J. Brice, Monongahela, Pa.

Application November 20, 1936, Serial No. 111,925

3 Claims. (Cl. 123—119)

This invention relates to a fuel saving device for internal combustion engines, and has for the primary object the provision of a device of this character which will provide more efficient acceleration, smoother operation and longer life to the engine and permit more power to be developed by said engine when operating under heavy loads.

With these and other objects in view, this invention consists in certain novel features of construction, combination and arrangement of parts to be hereinafter more fully described and claimed.

For a complete understanding of my invention, reference is to be had to the following description and accompanying drawing, in which

The figure is a side elevation, partly in section, illustrating a fuel saving device constructed in accordance with my invention.

20 Referring in detail to the drawing, the numeral 1 indicates an intake manifold of an engine and 2 an exhaust manifold. The intake manifold has a carburetor 3 connected thereto and 3' indicates the carburetor control valve. A fuel supply pipe 25 4 is connected to the carburetor. The parts described are common in the construction of an internal combustion engine and these parts have my invention connected thereto.

20 A pipe 5 is connected to the intake manifold adjacent the carburetor 3 and has branch pipes 6 and 7. The branch pipe 6 is equipped with a control valve 8 preferably of the needle type and to which a tube 9 is connected. The tube 9 is secured to and extends through a cover 10 of a container 11. The cover 10 is also provided with a vent means 12. A suitable lubricant is placed in the container 11 and by the suction developed in the intake manifold by the engine lubricant will be drawn from the container and delivered into the firing chambers of the engine by way of the intake manifold. The amounts in which the lubricant may pass to the engine may be varied by adjusting the valve 8. This lubricant entering 35 the engine or the firing chambers thereof will efficiently lubricate the pistons of the engine as well as the valves.

40 A mixing chamber 13 is connected at one end to the branch pipe 7 and its opposite end has connected thereto a control valve 14 which is manipulated manually by a control 15. The valve 14 is connected to the exhaust manifold 2 by a pipe 16. By adjusting the valve 14 the amount of exhaust entering the mixing chamber 13 can be 45 varied. A control valve 17 is arranged in the

mixing chamber 13 for regulating the flow of air and gases from the mixing chamber to the pipe 5 and is operatively connected to an accelerator 18 of the carburetor 3. A spring 19 is connected to the valve 17 for urging the latter into a closed position. A sleeve 20 is connected to the mixing chamber 13 and rises therefrom and forms a part of an air cleaner 21 consisting of a casing 22 perforated, as shown at 23, and has located therein a filtering material 24. The sleeve 20 10 extends upwardly in the casing 21 to a desired height above the filtering material so that air entering the casing before reaching the sleeve must pass through the filtering material.

From the foregoing description it will be seen 15 that exhaust gases and air may enter the mixing chamber 13 and pass into the engine by way of the pipe 5 and intake manifold and to be regulated by the throttle of the carburetor connected to the intake manifold.

20 A valve 25 of the needle type is connected to the casing 22 of the air filter and extends a limited distance into the sleeve 20 and has connected thereto a control valve 26. A pipe 27 connects the control valve 26 to the fuel supply pipe 25 4 and has a cutoff valve 28 therein. The control valve 26 is connected to the valve 17 by links and levers 29 so that when the valve 17 is moved towards an open position by the throttle 18 the valve 26 also will be opened to admit fuel to the 30 sleeve 20 which fuel may pass with the air into the mixing chamber 13 and there become mixed with the exhaust gases which raises the temperature of the air and fuel prior to reaching the intake manifold of the engine. At any time the 35 fuel to the air filter may be discontinued by closing the valve 28 and also the amount of fuel entering the air filter may be varied by adjusting the valve 25.

When the accelerator or throttle control 18 is 40 moved to increase the speed of the engine it simultaneously moves the valves 17 and 26 towards open position. The connection between the valve 17 and the throttle control 18 is of an adjustable character so that if desired the 45 throttle control 18 may have a certain amount of movement to open the carburetor before opening the valves 17 and 26. As the throttle control 18 is advanced to open the carburetor 3 an additional fuel mixture preheated will be 50 introduced into the intake manifold in addition to the fuel received from the carburetor which will provide quicker acceleration to the engine, smoother operation and more power. Also lubricant may be admitted to the engine along with 55

the additional supply of fuel from the container 11.

Having described the invention, I claim:

- 5 1. A fuel saver for engines comprising a mixing chamber, means for connecting said chamber to an intake manifold of an engine, means for connecting the mixing chamber to an exhaust manifold of the engine, a valve for controlling the escape of gases from the mixing chamber to said first means and actuated by a 10 throttle of a carburetor of the engine, an air cleaner connected to the mixing chamber and including a sleeve, means for admitting fuel to said sleeve, said sleeve receiving filtered air from the filter, and a valve for controlling the fuel to 15 the sleeve and actuated by the first-named valve.
- 20 2. A fuel saver for engines comprising a mixing chamber, means for connecting said chamber to an intake manifold of an engine, means for connecting the mixing chamber to an exhaust manifold of the engine, a valve for controlling the escape of gases from the mixing chamber to said first means and actuated by a 25 throttle of a carburetor of the engine, an air filter connected to the mixing chamber and in-

cluding a sleeve, means for admitting fuel to said sleeve, said sleeve receiving filtered air from the filter, a valve for controlling the fuel to the sleeve and actuated by the first-named valve, and a control valve for regulating the exhaust 5 gases to the mixing chamber.

3. A fuel saver for engines comprising a mixing chamber, means for connecting said chamber to an intake manifold of an engine, means for connecting the mixing chamber to an exhaust 10 manifold of the engine, a valve for controlling the escape of gases from the mixing chamber to said first means and actuated by a throttle of a carburetor of the engine, an air filter connected to the mixing chamber and including a 15 sleeve, means for admitting fuel to said sleeve, said sleeve receiving filtered air from the filter, a valve for controlling the fuel to the sleeve and actuated by the first-named valve, a control valve 20 for regulating the exhaust gases to the mixing chamber, and means for supplying and regulating lubricant to the intake manifold by way of said first means.

LEONARD J. BRICE.
